UNITED STATES PATENT OFFICE.

FRED CONTRADO, OF BOSTON, HUGO REINHOLD SWANSON, OF SOMERVILLE, AND ERIK MAURITZ SCHWARTZ, OF CAMBRIDGE, MASSACHUSETTS.

MATTRESS-FILLING MACHINE.

1,370,411.

Specification of Letters Patent.

Patented Mar. 1, 1921.

Application filed February 11, 1920. Serial No. 358,008.

To all whom it may concern:

Be it known that we, FRED CONTRADO, HUGO R. SWANSON and ERIK M. SCHWARTZ, citizens of the United States, and residents, respectively, of Boston, county of Suffolk, State of Massachusetts, Somerville, county of Middlesex, State of Massachusetts, and Cambridge, county of Middlesex, State of Massachusetts, have invented Improvements 5 in Mattress-Filling Machines, of which the following description, in connection with the accompanying drawing, is a specification, like characters on the drawing representing like parts.

15 This invention has for its object to provide a novel mattress-filling machine of the type arranged to deliver the mattress filling material to the mattress by means of a blast of air, and the object of the invention 20 is to provide an improved machine of this type which is extremely simple in construction; which operates to thoroughly fluff up the filling material before introducing it into the mattress and separate therefrom any 25 seeds, sticks or other similar foreign matter, and which has other advantages, all as will be more fully hereinafter set forth.

In order to give an understanding of our 30 invention, we have illustrated in the drawings a selected embodiment thereof which will now be described, after which the novel features will be pointed out in the appended claims.

35 In the drawings, Figure 1 is a side view with a portion broken out showing an apparatus embodying our invention;

Fig. 2 is a top plan view of the tank;

Fig. 3 is a section on the line 3—3, Fig. 1.

Fig. 4 is a transverse sectional view 40 through the delivery end of the pipe 8.

Our apparatus comprises a tank or chamber 1 which is open at the top, as shown at 2, the open top preferably being provided with a fine screen 3. The apparatus also includes a fan or blower 4 having its inlet 45 connected to the bottom of the tank by a suitable pipe 5 and having its discharge connected to a delivery pipe 6 which is branched, one branch 7 thereof extending 50 into the top of the tank and the other branch 8 being constructed to have a mattress to be filled secured thereto.

The pipe 5 is provided with a filling hopper 9 which leads thereinto, said hopper 55 having a cover or closure 10 by which it

may be closed. This hopper is for the purpose of introducing the mattress filling material into the pipe 5.

The branch pipe 6 is provided with a valve or gate 11 situated at the junction of 60 the branches 7 and 8, said valve being constructed so as to close either branch for a purpose presently to be described.

The chamber 1 is provided near its bottom with a perforated partition 12, said 65 partition being situated below the point where the pipe 5 communicates with said chamber. The apertures in this partition are of sufficient size to permit seeds, sticks and similar foreign material to pass therethrough. The branch 8 is shown as extending directly through the tank 1, and the end thereof is provided with clamping means 13 by which an open end of a mattress 70 14 to be filled may be secured thereto. 75 This means may assume various forms without departing from the invention. We have herein illustrated a clamp comprising two clamping jaws 13 which clamp the mouth of the mattress to the end of the pipe. In 80 the operation of the device the cover 10 of the hopper 9 will first be removed and a quantity of the material used for filling the mattress will be inserted through the hopper into the pipe 5. The hopper is then 85 closed and the gate 11 is turned into the full line position, Fig. 1, so as to close the branch 8 while leaving the branch 7 open. The fan is then set in operation, and this will cause an air current to circulate in the 90 direction of the arrows. This will result in drawing the filling material through the fan and delivering it to the top of the tank 1 where it settles to the bottom and is withdrawn again through the pipe 5. As the 95 filling material is passed through the fan, it becomes broken or fluffed up, and any seeds, stems, sticks or other similar material may be thoroughly separated from the fluffy material.

100 As the filling material passes into the chamber 1 it will settle gradually to the bottom and the heavy ingredients, such as the seeds, stems, etc., will fall on the grating 12 and pass through the holes therein, 105 while the lighter fluffy material which is desirable for filling mattresses will be again taken through the fan. By thus continuously passing the material through the fan for a short time, it becomes entirely freed 110

from any sticks, seeds, stems, etc., and assumes an extremely light and fluffy condition. The seeds, sticks, stems, etc. become separated and drop onto and through the 5 grating 12 so that after a short time the material is not only fluffed up to the desired point, but is also separated from the undesirable ingredients. After this operation has been carried on for a sufficient 10 length of time the mattress 14 will be attached to the end of the branch 8 and the gate 11 will be shifted into the dotted line position, thereby directing the fluffed-up filling 15 material into the mattress.

15 If desired the mattress may be placed on a suitable weighing apparatus 15 so that it can be given the desired weight.

If the amount of material which is first introduced in the hopper 9 is insufficient to 20 properly fill the mattress, then the gate 11 may be shifted into position to close the branch 8 and an added quantity of material can be delivered to the pipe 5 through the hopper 9. After this added material has 25 been sent around the circuit a sufficient number of times to properly fluff it up and free it from any sticks or stems, then such material can be introduced into the mattress by shifting the gate 11. It will thus be ob- 30 served that our apparatus not only fluffs up the material, but also separates it from the seeds, stems, etc.

We find that it is highly advantageous to have the top of the chamber 1 open as indicated and to withdraw the material from the bottom of the chamber and introduce it into the top, for by this means a better separation of the seeds and similar material from the fluffy material is secured.

40 We have herein shown the tank 1 as having a door 16 through which access can be had to said tank if desired.

While we have illustrated one selected embodiment of our invention, we do not

wish to be limited to the constructional features shown.

We claim:

1. In a mattress-filling machine, the combination with a chamber open at its top, of a fan, a pipe connecting the fan inlet to 50 the lower end of said chamber, a delivery pipe connected to the fan discharge, said delivery pipe being branched and one branch leading into said chamber near its top and the other having provision for attaching a 55 mattress thereto, and a gate to close either branch.

2. In a mattress-filling machine, the combination with a chamber open at its top, of a fan, a pipe connecting the lower end of 60 the chamber to the fan inlet, said pipe having a filling hopper communicating therewith, a closure for said hopper, a delivery pipe connected to the fan discharge, said delivery pipe being branched and one branch 65 leading into the chamber near its top and the other having provision for attaching a mattress thereto, and a gate to close either branch.

3. In a mattress-filling machine, the combination with a chamber open at its top, of a fine screen across the opening, a grating within the chamber near the bottom thereof, a fan, a pipe connecting the chamber above the grating to the fan inlet, said 75 pipe having means for introducing mattress-filling material thereinto, a branched delivery pipe connected to the fan discharge, one branch leading into the chamber near the top and the other having provision for 80 attaching a mattress thereto, and a gate for closing either branch.

In testimony whereof, we have signed our names to this specification.

FRED CONTRADO
HUGO REINHOLD SWANSON.
ERIK MAURITZ SCHWARTZ.
